JOHN F. DOEHLE, OF PLAINFIELD, NEW JERSEY.

CONVEYER.

No. 846,402.

Specification of Letters Patent.

Patented March 5, 1907.

Application filed December 22, 1905. Serial No. 292,912.

To all whom it may concern:

Be it known that I, JOHN F. DOEHLE, a subject of the Emperor of Germany, and a resident of the city of Plainfield, in the county of Union and State of New Jersey, United States of America, have invented certain new and useful Improvements in Conveyers, of which the following is a specification.

My invention relates to bucket conveyers; and its object is to provide a simple and cheap construction for conveyers of this type which will have many advantages over those now in use.

I will now describe my invention in the following specification and point out the novel features thereof in claims.

Referring to the drawing, Figure I is a vertical section through the line 1 2 of Fig. II of a part of my conveyer. Fig. II is a side elevation of a part of my improved conveyer, showing the manner in which the various parts are connected together and also a device for loading the conveyer. Fig. III is a side elevation, on a smaller scale, of a part of one of my improved conveyers, showing one form of driving mechanism and also showing its track with vertical curves. Fig. IV is a plan view of similar parts, showing the conveyers with horizontal curves. Figs. V and VI are respectively end and side elevations of an arrangement which I use for automatically dumping the buckets of the conveyer.

Like characters of reference designate corresponding parts in all of the figures.

A designates a rigid track or traction-rail. It is here shown as an ordinary channel-iron, as this is a preferred construction. B B designate rods which suspend this rail from any desired structure. These rods B B may be run through the channel-iron and have cross-pieces C placed through them upon which the channel is supported. The other end of these rods may be attached to a rope or cable 11, which may be supported upon poles 10, or they may be attached to a rafter 12 of a building, if desired. A plurality of trolleys are arranged to run upon this traction-rail A. In Fig. I it may be seen that these trolleys comprise two flanged wheels D D, which are supported upon suitable brackets E E, which extend from the wheels D downward on either side of the rail A and are joined together by bolts or screws, as shown at F.

A haulage-cable G is arranged to connect the various brackets or hangers of the trol-

leys, and this cable may be rigidly connected to the brackets E E where the brackets are connected together at F. This haulage-cable may be made of any desired material— such, for example, as chain or rope—and the various trolleys may be attached to it at equal distances from each other. One of the brackets E is extended downward, as shown at E', and a hinge-piece J may be attached to it by means of a bolt H. Another bolt H' may be inserted in this hinge-piece at right angles to the bolt H and arranged to support a strap N.

L L designate buckets. Upon each side of these buckets are loops M M, which are connected to the straps N N by links K K. It may be seen then that the buckets are supported upon the trolleys by means of these links K K and that between the links and the lower ends E' of the trolley-brackets is a universal joint formed by the hinge-piece J and the two bolts H and H', which pass through it. These parts are preferably so arranged that the buckets L L are held apart from each other a certain amount, so that they may not interfere with each other when they are driven about curves in a manner which will be pointed out later. This construction leaves a space between the buckets, and it is desirable to have this space properly covered in order that no material may fall between the buckets when it is running through a chute into the buckets, as will be fully pointed out later. For this purpose I provide plates O, which may be connected, as shown in Figs. I and V, to the hinge-piece J by means of links I. These plates are arranged to rest upon the upper part of buckets L, and in order to support them and keep them from dropping in between the buckets when they run around a curve brackets P P, formed of angle-irons, may be attached to the side of the buckets and arranged to support the plates. The upper portion O' of these plates may be extended over the hinge-piece J and may rest upon the same.

X designates a chute through which material may be passed into the buckets L L. It is often desirable to fill these buckets while they are moving, and in order that this may be done simply it is desirable to pass material through the chute X continuously. The lower opening of the chute is placed directly above the mouths of the buckets, so that the material passes into the buckets which are directly below the chute. As the buckets pass the

lower end of the chute, however, the material will be caught upon the plate O, which covers the space between adjoining buckets, and some of the material will therefore rest upon the plate O. The chute is, however, preferably provided with a vertical plate X', which is situated directly above these plates and is arranged to scrape off such material as has accumulated on the plate into the next bucket. The chute may of course be placed in any desirable position along the line of travel of the conveyer. The center of gravity of the buckets is preferably on the opposite side from that into which the material passes, so that they will normally maintain an upright position. Any tendency of the weight of material in the buckets to tilt the buckets so that their mouths would be raised above a horizontal position may be stopped by the flanged portions O' of the plates O, which rest upon the hinge-piece J and prevent a farther upward movement of the mouths of the buckets. This flanged portion O' also serves the purpose of protecting the hinged joints by which the buckets are supported to the trolleys. A projecting roller Q may, however, be provided upon each bucket, and guide-rails, such as R, (shown in Fig. I,) may be provided opposite the chute X for the purpose of steadyng the buckets while they are being filled and preventing the material which falls into the buckets from tipping them over. Wherever it is desired to discharge the material, another guide-rail S may be provided, which will engage with the projecting rollers Q and act as a cam to raise the under portion of the buckets, as is shown in Figs. V and VI, and to again bring them back to their normal position. This cam-rail S may of course be situated at any desired point along the path of travel of the conveyer. When the buckets are tilted in the manner just described, the plates O, which are attached to the hinge-piece J by links I, will also be tilted sufficiently to allow any material which has not been scraped off from them to slide off. This is clearly shown in Fig. V.

Referring now to Fig. III, it may be seen that the track A is constructed with two vertical curves. With my construction it is perfectly feasible for the conveyer-buckets to be run over such curves. Of course in doing so the distance between the buckets will be increased or decreased; but by the arrangement of hanging them which I have invented this does not interfere with their operation in any way. When the trolleys are run over an upward curve in the track, it is desirable to place a guard-rail W over them in order to prevent the tension on the haulage-cable G from lifting them from the track A. T designates a driving-wheel for the haulage-cable G, which may be rotated by any suitable motive power. This wheel T may be provided

with recesses T', as shown in Fig. IV, which are provided for the purpose of allowing the hanging brackets E to pass this wheel without interference.

In Fig. IV the buckets are shown passing around horizontal curves, and in this case the wheels U and V V are preferably provided for the purpose of guiding the haulage-cable. These wheels may be provided with recesses U' and V' for allowing the hanger-brackets E to pass the wheels without interference. Of course these wheels may be provided with means for adjusting their position in order to keep the haulage-cable G at proper tension in any of the well known manners.

This bucket-conveyer system which I have invented may be very cheaply constructed, and because of the fact that the track which carries the bucket is suspended by rods it may be readily set up either in a building or in a field, for the rods B may be simply attached to a rope or cable 11 and this cable supported in any simple manner.

The construction work for the track may be made with very little weight compared with the amount of work which the conveyer is capable of doing. It is also a very simple conveyer to maintain and keep in order, as all of its parts are accessible for lubrication and for repairs.

The construction which I have specifically described is merely to illustrate the use of my invention, which, of course, may be constructed in many different ways—for example, the universal joint may be dispensed with, or the buckets may be suspended by means of chains instead of links.

What I claim is—

1. In a conveyer, a rigid track, supports arranged to suspend and hold the track, a series of trolleys connected together and arranged to run upon the track, a series of buckets and links connecting adjacent buckets, said links being connected to the trolleys.

2. In a conveyer, a rigid track, a stationary cable, rods connecting the track to the cable, a series of trolleys connected together and arranged to run upon the track, each of said trolleys comprising a pair of wheels with one wheel on either side of the rods, a series of buckets, links connecting adjacent buckets, said links being connected to the trolleys.

3. In a conveyer, a rigid track having vertical and horizontal curves, supports arranged to hold and suspend the track, a series of trolleys arranged to run upon the track, a haulage-cable to which said trolleys are connected, a series of buckets, and links connecting each bucket to two of said trolleys.

4. In a conveyer, the combination of a series of connected buckets, a rigid track, supports arranged to suspend and to hold the track, trolleys arranged to run on the track, each of said trolleys comprising a pair of

wheels, one of said wheels on either side of the track-supports, and links arranged to flexibly connect the buckets together and to flexibly connect each of said buckets to two of said trolleys.

5. In a conveyer, a suspended rigid track therefor, rods arranged to support the track, trolleys arranged to run on the track, each of said trolleys comprising a pair of wheels with one wheel on either side of the rods, brackets arranged to support the wheels, a series of buckets and intermediate connections between the brackets and the buckets arranged to flexibly connect each of the buckets to two of the brackets.

6. In a conveyer, the combination of a series of hanging buckets, a rigid track having horizontal and vertical curves and links flexibly connecting the buckets together and to the track.

7. In a conveyer, a track therefor, a plurality of trolleys arranged to run on said track connections between the trolleys and a plurality of buckets flexibly connected to the trolleys and also to each other.

8. In a conveyer, a track therefor, a plurality of trolleys arranged to run on said track, a plurality of buckets and links connecting the buckets to the trolleys and to each other.

9. In a conveyer, a rigid track therefor, a plurality of trolleys arranged to run on said track, a haulage-cable, said trolleys being rigidly connected to the cable, and a plurality of buckets flexibly connected to the trolleys and also to each other.

10. In a conveyer, a suspended rigid track therefor, a plurality of trolleys arranged to run on said track, a plurality of buckets, links arranged to connect the buckets to the trolleys and to each other, and a haulage-cable connected to the trolleys.

11. In a conveyer, a suspended rigid track therefor, a plurality of trolleys arranged to run on said track, brackets on either side of the track, a plurality of buckets links flexibly connecting the buckets to the brackets and to each other, a haulage-cable for the trolleys, said brackets being rigidly connected to the haulage-cable.

12. In a conveyer, a suspended rigid track therefor, a plurality of trolleys arranged to run on said track, brackets on either side of the track, a plurality of buckets flexibly connected to the trolleys and to each other, a haulage-cable for the trolleys, said brackets being rigidly connected to the haulage-cable and means for positively driving said haulage-cable.

13. In a conveyer, a suspended rigid track therefor, a plurality of trolleys arranged to run on said track, brackets on either side of the track, a plurality of buckets flexibly connected to the trolleys and to each other, a

haulage-cable for the trolleys, said brackets being rigidly connected to the haulage-cable, and wheels arranged to drive said haulage-cable, said wheels being provided with recesses for said brackets.

14. In a conveyer, the combination of a suspended rigid track, a plurality of trolleys arranged to run on said track, a plurality of buckets flexibly connected to the trolleys and to each other, and plates arranged to cover the space between said buckets.

15. In a conveyer, the combination of a suspended rigid track, a plurality of trolleys arranged to run thereon, wheels for said trolleys, brackets for supporting the wheels, a plurality of buckets and a universal joint between each trolley and buckets.

16. In a conveyer, the combination of a suspended rigid track, a plurality of trolleys arranged to run thereon, wheels for said trolleys, a plurality of buckets, brackets, and links arranged to connect said buckets to said trolleys and to each other and plates arranged to cover the space between the buckets, said plates being flexibly connected to the brackets.

17. In a conveyer, the combination of a suspended rigid track, a plurality of trolleys arranged to run thereon, wheels and brackets for said trolleys, a plurality of buckets, links arranged to connect said buckets to said brackets, and to each other and plates arranged to rest upon the buckets and to cover the space between the buckets, said plates being flexibly connected to the brackets and arranged to move freely in one direction but not in the opposite direction.

18. In a conveyer, the combination of a suspended rigid track, a plurality of trolleys arranged to run thereon, wheels and brackets for said trolleys, a plurality of buckets, links arranged to connect the buckets to the trolleys and to each other, plates arranged to cover the space between the buckets, said plates being connected to the brackets, a haulage-cable connected to said brackets and a chute above the path of travel of the buckets.

19. In a conveyer, the combination of a suspended rigid track, a plurality of trolleys arranged to run thereon, wheels for said trolleys, a plurality of buckets, links arranged to connect the buckets to the trolleys and to each other, plates arranged to cover the space between the buckets, said plates being connected to the buckets, a haulage-cable connected to said brackets and a chute above the path of travel of the buckets, said chute being provided with a scraping-surface.

20. In a conveyer, the combination of a suspended rigid track, a plurality of trolleys arranged to run thereon, wheels for said trolleys, a plurality of buckets, links arranged to connect the buckets to the trolleys and to each other, plates arranged to cover the

space between the buckets, said plates being connected to the brackets, a haulage-cable connected to said brackets, a chute above the path of travel of the buckets, a projection upon each bucket and means opposite the chute arranged to engage with said projections and to steady the buckets while they are being filled.

21. In a conveyer, the combination of a suspended rigid track, a plurality of trolleys arranged to run thereon, wheels and brackets for said trolleys, a plurality of buckets, and links arranged to connect the buckets to the trolleys and to each other, plates arranged to cover the space between the buckets, said plates being connected to the brackets, a haulage-cable connected to said brackets, a chute above the path of travel of the buckets, a projection upon each bucket and means for automatically tilting the buckets by their own movement.

22. In a conveyer, the combination of a suspended rigid track, a plurality of trolleys arranged to run thereon, wheels for said trolleys, brackets for said wheels, a plurality of buckets, links arranged to connect the buckets to the brackets and to each other, plates arranged to cover the space between the buckets, said plates being connected to the brackets, a haulage-cable, said brackets being connected to the haulage-cable at equal intervals, and a wheel for positively driving the haulage-cable.

23. In a conveyer, the combination of a suspended rigid track, a plurality of trolleys arranged to run thereon, wheels for said trolleys, brackets for said wheels, a plurality of buckets, and links arranged to connect the buckets to the trolleys and to each other, plates arranged to cover the space between the buckets, said plates being connected to the brackets, a haulage-cable connected to said brackets, a chute above the path of travel of the buckets, a projection upon each bucket, means opposite the chute arranged to engage with said projections and to steady the buckets while they are being filled, and a cam arranged to engage with said projections and to tilt the buckets by their own movement.

24. In a conveyer, the combination of a suspended rigid track, a plurality of trolleys arranged to run thereon, wheels for said trolleys, brackets for the wheels, a plurality of buckets, and links arranged to connect the buckets to the trolleys and to each other, plates arranged to cover the space between the buckets, said plates being connected to

the brackets, a haulage-cable connected to said brackets, a chute above the path of travel of the buckets, a projection upon each bucket, means opposite the chute arranged to engage with said projections and to steady the buckets while they are being filled, and a cam arranged to tilt the buckets over and back again by their own movement.

25. In a conveyer, the combination of a suspended rigid track, supporting-rods therefor, a cable, said rods being attached to the track and to the cable, a plurality of trolleys arranged to run on the track, flanged wheels for said trolleys, brackets for supporting said wheels, a plurality of buckets, links arranged to connect the buckets to the brackets and to each other, a universal joint interposed between the links and the brackets, plates arranged to cover the space between the buckets, said plates being connected to the brackets and arranged to prevent the tilting of the buckets in one direction, a haulage-cable, said brackets being attached to the haulage-cable at equal intervals, a wheel arranged to drive the haulage-cable, a chute above the path of travel of the buckets, a projecting roller upon each bucket, means opposite the chute arranged to engage with said projections and to steady the buckets while they are being filled and a cam arranged to tilt the buckets over and back again by their own movement.

26. In a conveyer, the combination of a rigid track, supports for suspending and holding the track, trolleys arranged to run on the track and links connecting each bucket to two of said trolleys, said links being arranged to allow the distances between the buckets to vary.

27. In a conveyer, the combination of a series of buckets, means for connecting the buckets together, said means being arranged so that the distance between the buckets may vary, a rigid track, supports arranged to suspend and to hold the track, trolleys arranged to run on the track, each of said trolleys comprising a pair of wheels, one of said wheels on either side of the track-supports, and links arranged to flexibly connect the buckets together and to flexibly connect each of said buckets to two of said trolleys.

In testimony whereof I have signed my name to this specification in the presence of two subscribing witnesses.

JOHN F. DOEHLE.
